(57) **CLAIM**

The ornamental design for a touch panel for scanner with graphical user interface, as shown and described.

DESCRIPTION

FIG. 1 is a front perspective view of the first image in the sequence of the touch panel for scanner with graphical user interface showing our new design;

FIG. 2 is a front view thereof;

FIG. 3 is a top plan view thereof;

FIG. 4 is an enlarged view thereof;

FIG. 5 is a front view of the second image thereof;

FIG. 6 is a front view of the third image thereof;

FIG. 7 is a front view of the fourth image thereof; and,

FIG. 8 is a front view of the fifth image thereof.

The broken line showing of the scanner illustrates the environment of the claimed design and forms no part thereof.

The appearance of the graphical user interface transitions between the images shown in FIGS. 4-8. The process or period in which one image transitions to another image forms no part of the claimed design.

1 Claim, 4 Drawing Sheets
